(57) **CLAIM**

The ornamental design for a flexible mount for phone grip, as shown and described.

DESCRIPTION

FIG. 1 is a top perspective view of the flexible mount for phone grip according to the present invention;

FIG. 2 is a top view thereof;

FIG. 3 is a bottom view thereof;

FIG. 4 is a left side view thereof;

FIG. 5 is a right side view thereof;

FIG. 6 is a first end view thereof;

FIG. 7 is a second end view thereof;

FIG. 8 is a top perspective view thereof in a different arrangement;

FIG. 9 is a first view of the arrangement shown in FIG. 8;

FIG. 10 is a second view of the arrangement shown in FIG. 8;

FIG. 11 is a left side view of the arrangement shown in FIG. 8;

FIG. 12 is a right side view of the arrangement shown in FIG. 8;

FIG. 13 is a top view of the arrangement shown in FIG. 8; and,

FIG. 14 is a bottom view of the arrangement shown in FIG. 8.

The dash-dash broken lines depict portions of the article that form no part of the claimed design and the dash-dot-dash broken lines represent the bounds of the claim and form no part thereof.
